UNITED STATES PATENT OFFICE.

ADOLPH P. GUSTAFSON, OF CHICAGO, ILLINOIS, ASSIGNOR TO M. SCHULZ CO., OF CHICAGO, ILLINOIS.

ACTION FOR PLAYER-PIANOS AND THE LIKE.

1,101,846.

Specification of Letters Patent. Patented June 30, 1914.

Application filed May 10, 1912. Serial No. 696,307.

To all whom it may concern:

Be it known that I, ADOLPH P. GUSTAFSON, a citizen of the United States, residing at Chicago, in the county of Cook and State 5 of Illinois, have invented a certain new and useful Improvement in Actions for Player-Pianos and the like, of which the following is a full, clear, concise, and exact description, reference being had to the accompanying 10 drawings, forming a part of this specification.

My invention relates to an improvement in actions for player pianos and the like, and has as its principal object the provision of a 15 more efficient and economical arrangement than that shown in my copending application, Serial No. 597,069, for mechanical musical instruments, filed December 13, 1910.

A further object of my invention resides 20 in the particular arrangement and combination of parts hereinafter described.

In the accompanying drawings, Figure 1 is a plan view of a portion of an action having my improved apparatus shown with the 25 top board removed, parts being broken away; Fig. 2 is a cross sectional view on the line 2--2 of Fig. 1, looking in the direction of the arrows, and showing the top board in place.

Referring more particularly to the drawings, 30 1 is a block which together with the cover plate 2 incloses a wind chest 3. It will be seen from inspection of the drawings that the block 1 is integral, there being only two 35 members necessary in order to inclose the wind chest 3. Moreover, it will be apparent that no part of the ports or passages in the member 1 will need to be plugged after drilling. A wind-way 4 connects the chest 3 40 with the suction apparatus. As appears in Fig. 2, in particular, there are at least two wind chests, one above the other, with their accompanying apparatus. Attached to the under side of the block 1 are action pneumatics such as 5. In Fig. 2 the lower pneumatic is shown collapsed as in causing a note to be sounded while the upper pneumatic is shown extended in its normal or quiescent position. Leading from the pneumatics 5 45 are passages 6 which connect with valve chest 7. Leading from the lower part of the valve chest 7 are ports 8 which connect with

grooves or passages 9 in the lower face of the block 1. These grooves 9 connect with the atmosphere. Covering the upper part of 55 the valve chest 7 is a metal plate 10 provided with a port 11, which connects with the interior of the wind chest 3. Within the chest 7 is mounted a valve 12 which is adapted to close either of the ports 8 or 11 in turn. The 60 valves 12 are formed of wood having coverings of leather on their opposite faces, and are supported by hooks 13. These hooks extend through openings in the upper leather cover of the valves, as clearly illustrated in 65 the drawings, so that the valves may swing in any direction necessary in order to register properly with the surface of the valve ports. The hooks which support the faces are formed on the ends of wire parts or rods 70 14 which are attached to the movable members 15 of the small pneumatics mounted in the interior of the chest 3. Movable members 15 are drilled and provided with metal pieces 16 having bleed holes therein forming 75 communication between the interior of the small pneumatics and the wind chest 3. The bottoms of the small interior pneumatics are drilled to connect with tracker tubes such as 17. As shown in Figs. 1 and 2 the 80 blocks 1 are chiseled to form shoulders as at 18 against which the small interior pneumatics abut, and leaving a groove or recess 19 within which they are mounted. Said groove or recess is inclined downwardly 85 away from the shoulder. This saves vertical space, since it gives the weighted end of the pneumatic room to expand and at the same time allows the chest to be made thin in the vertical direction. The members 15 90 of the small interior pneumatics are slotted to receive weights 20 which normally hold them depressed as shown in the upper pneumatic in Fig. 2.

In the operation of my device the small 95 interior pneumatics are normally exhausted through the pin hole in the member 16, so that the weights 20 hold them in the position shown in the upper pneumatic of Fig. 2. Consequently the valve 12 is held against its 100 upper seat and air may enter the striking pneumatics through the groove 9 and the communicating passages. When, however, air is admitted into the small interior pneu-

matic through one of the tubes 17 it is inflated, as shown in the lower one of the devices in Fig. 2, thus cutting off communication between the valve chest 7 and the atmosphere, and connecting the corresponding striking pneumatic 5 with the tension. The small interior pneumatics used in this construction have an advantage over the ordinary pouches employed in that they are noiseless in their action. Furthermore the use of the interior pneumatics avoids pivoting the rods on which the valves are carried, the pivot of the pneumatic being sufficient, and also avoids having to bend these valve rods as in my former application.

Having thus described my invention, what I claim is:

1. In a pneumatic instrument in combination, a pneumatic having fixed and movable sides pivoted together along one end, a substantially horizontal block on which said fixed member is supported, said block having a valve chest therein, an apertured plate partially closing the upper face of said chest, a valve in said chest below said plate, and a rod attached to said movable member extending through the aperture in said plate provided with an open hook at one edge for engaging the upper part of said valve.
2. The combination of a pneumatic having a hinged swinging leaf provided with an arm extending longitudinally from the hinged end of said swinging leaf and carrying a valve the weight of which is supported by said arm, said swinging leaf having its swinging end provided with a weight to counterbalance said valve.
3. In a device of the class described, a wind chest having a recess therein and a shoulder at the edge of said recess, primary pneumatics mounted in said recess abutting against said shoulder, said primary pneumatics having weighted movable members, a rod attached directly to one of said movable members and having a hooked end, and a valve suspended from said end.
4. In a device of the class described in combination, a block forming one side of a wind-chest, said block having an elongated recess or groove and having a shoulder at the edge of said recess, and a pneumatic provided with fixed and movable members, said fixed member having one end abutting against said shoulder.
5. In a device of the class described in combination, a block forming one side of a wind-chest, said block having an elongated recess or groove and having a shoulder at the edge of said recess, and a pneumatic provided with fixed and movable members, said fixed member having one end abutting against said shoulder, and said fixed member having a thickness substantially equal to the height of said shoulder and said mov-

able member being pivoted to the fixed member at the end adjacent said shoulder.

6. In a pneumatic instrument in combination, a wind-chest comprising blocks forming opposite sides of the chest, one of said blocks having a groove or elongated recess therein inclosed on one side by a shoulder, the floor of said recess sloping at an obtuse angle to said shoulder, and a pneumatic comprising fixed and movable members, said fixed member being attached to the sloping floor of said recess and abutting against said shoulder.

7. In a device of the class described, a valve actuating pneumatic comprising a leaf pivoted at one end, said leaf being mounted in a substantially horizontal position, an operating weight carried by said leaf at the end opposite its pivot, and a hooked rod carried by and extending longitudinally of and from said leaf.

8. In a device of the class described, a valve actuating pneumatic comprising a leaf pivoted at one end, said leaf being mounted in a substantially horizontal position, an operating weight carried by said leaf at the end opposite its pivot, a rod having one end in the form of an open hook carried by and extending longitudinally of and from said leaf, and a valve hung directly on the hooked end of said rod.

9. In a device of the class described in combination, a valve actuating pneumatic having a pivoted movable member, a rod attached directly to said movable member and having a hooked end, said member being weighted at the end removed from said rod, and a valve pivotally mounted directly on the hooked end of said rod.

10. The combination of a structure forming a wind chest, a pneumatic having a hinged swinging leaf arranged within said wind chest, said swinging leaf having a rod or arm extending longitudinally from its hinged end, a valve supported at the other end of said arm or rod, ports above and below said valve, a duct running to the space between said ports, a duct or passage communicating with the interior of said pneumatic, and a power pneumatic having a port communicating with the duct or passage extending from the space between said port, said power pneumatic being secured to the under side of said wind chest structure.

11. The combination of a structure forming a wind chest, a primary pneumatic arranged within said wind chest and having a hinged swinging leaf, from the hinged end of which extends a rod or arm carrying a valve, a metallic member forming a port and arranged above said valve, a port on the side of said valve opposite said member and an air recess formed in said structure and communicating with said last mentioned

port, a duct extending from the valve space between said last mentioned ports, a pneumatic secured to said wind chest structure and communicating with the duct or passage 5 extending from said valve space, and a tracker board passage communicating with the interior of said primary pneumatic.

In witness whereof, I hereunto subscribe my name this 18th day of April A. D., 1912.

ADOLPH P. GUSTAFSON.
